UNITED STATES PATENT OFFICE

2,479,179

THERMOSTATICALLY OPERATED
ELECTRIC SWITCH

Carl V. Newbill, Portland, Oreg.

Application July 20, 1948, Serial No. 39,613

1 Claim. (CL 200—118)

1

This invention relates generally to electric switches and particularly to those which are thermostatically operated.

The main object of this invention is to provide a normally open switch adapted to be closed whenever an arc is formed across the contact points of the switch.

The second object is to provide a convenient and inexpensive means for reducing the hazards and inconveniences caused by leaks which occur in installations where a section of a gas tube sign has become inoperative.

I accomplish these and other objects in the manner set forth in the following specification as illustrated in the accompanying drawing, in which:

Fig. 1 is a diagrammatic view showing the manner in which the switch is installed.

Fig. 2 is a longitudinal section through the device, showing its normal position.

Fig. 3 is an end elevation of Fig. 2.

Fig. 4 is a view similar to Fig. 2 but showing the switch in a closed position.

Fig. 5 is a section on the line 5—5 of Fig. 4.

Like numbers of reference refer to the same or similar parts throughout the several views.

Referring in detail to the drawing, there is shown a sign composed of the letters 10, 11 and 12 which, in this case, spell out the word "gas." Current is supplied from a transformer 13 which is fed from a power line 14.

High voltage current is supplied to the gas filled tubes 10, 11 and 12 from the transformer 13 through the leads 15 and 16.

The letter 10 is connected to the letter 11 by means of a lead 17. The letter 11 is connected to the letter 12 by means of the lead 18. Such installations are in common use.

Referring particularly to my invention, which resides in the switch itself, same consists of a glass tube 19, the ends of which are closed by the corks 20 and 21. Through the corks 20 and 21 extend the electrodes 22 and 23 whose innermost ends terminate in rings 24 and 25 which are spaced from each other but which may lie as close to the tube 19 as desired.

On the adjacent ends of the electrodes 22 and 23 are mounted the metallic caps 26 and 27 which fuse at a relatively low temperature. The convex faces 28 and 29 of the caps 26 and 27 are spaced from each other and constitute a gap which will not be jumped by the current as long as it can flow across its respective gas filled tube 10, 11 or 12.

One electrode 22 is joined to the lead 17 and

its companion electrode 23 is joined to the lead 15, forming a shunt switch around the letter 10. That is, if the tube 10 should fail and no current pass therethrough, the current would arc across the space between the caps 26 and 27 and fuse them, bringing about a condition as shown in Fig. 4 and restoring the remainder of the sign as well as avoiding the charging of the fixture with a high potential current.

10 Between the leads 17 and 18 of the letter 11 is placed a second switch whose electrode 22 is joined to the lead 17 and whose electrode 23 is joined to the lead 18.

15 Between the leads 18 and 16 is placed a third switch whose electrode 22 is joined to the lead 18 and the electrode 23 is joined to the lead 16.

It can be seen from the foregoing that, regardless of the positions of the sign or switches, any arc formed across the caps 26 and 27 will 20 fuse them and permit current to flow directly across the bridge between the electrodes 22 and 23.

When installing these switches, no special brackets or mounts are required as their light 25 weight makes it possible to suspend them from their own electrodes 22 and 23.

Attention is drawn to my U. S. Patent 2,464,-340, over which the present invention is an improvement.

20 I claim:

A switch of the class described consisting of a glass tube having a cork plug closing each end thereof, each of said plugs having an axial electrode extending therethrough, the innermost end 35 of each electrode having a ring formed thereon, normal thereto, each of said rings having mounted thereon a fusible cap, the adjacent faces of which are spaced from each other, the volume of metal in said caps being sufficient to 40 bridge the gap between said rings when said caps are fused in any position.

CARL V. NEWBILL.
